UNITED STATES PATENT OFFICE

HUMPHREY JOHN DENHAM, OF MANCHESTER, ENGLAND, ASSIGNOR TO HENRY SIMON LIMITED, OF MANCHESTER, ENGLAND, A BRITISH COMPANY

FREE-SWINGING MECHANISM FOR IMPARTING RECIPROCATORY MOVEMENTS

Application filed July 27, 1928, Serial No. 295,812, and in Great Britain May 11, 1928.

This invention relates to what are known as free swinging mechanisms for imparting reciprocatory movements to screens, conveyors, sieves and the like, the mechanism being carried by the part to be reciprocated.

5 The object of this invention is to provide improved and simplified means of the type aforesaid and it comprises a frame having a crank shaft journalled therein and a slotted and weighted lever pivoted thereon, the crank pin of said shaft acting upon said lever so that unequal rates of acceleration are imparted thereto on the rotation of the shaft, the inertia of the weighted lever relatively to that 10 of the complete structure or mass to be reciprocated and by which the said free swinging mechanism is carried, resulting in the desired reciprocation of said mass at unequal rates on the forward and return strokes and with a jiggling or jerking motion such as is 15 desired in screens and the like.

Referring to the two accompanying sheets of explanatory drawings:—

Figure 1 is a sectional side elevation and 25 Figure 2 a sectional end elevation illustrating a convenient application of the invention.

Like reference letters in the two views indicate like parts.

As shown in the drawings, the rotating 30 crank shaft *a* and crank disc *b* with the crank pin *c* projecting from one side of the same are enclosed within a frame or casing *d* by which the crank shaft *a* is carried; the said frame *d* also pivotally supports the slotted and 35 weighted lever *e*. The frame or casing *d* is secured to and carried by the suspended screen or like part *f* to be reciprocated. The engagement between the crank pin *c* and lever *e* includes a block or slipper *g* adapted to slide 40 between the sides of the lever gap or slot, the said sides serving as guides.

The position of the lever gap or slot relatively to the rotating crank pin *c* is such that whilst each revolution of the said pin effects 45 a complete reciprocation or back and forth movement of the lever *e*, the driving contact between the crank pin and the lever occurs, throughout such revolution, at constantly varying distances from the fulcrum or supporting pivot *h* of the weighted lever. Due

to the inertia of the latter and its arrangement as aforesaid, unequal accelerations and jiggling or jerking movements are imparted to the member *f* being reciprocated and by which the mechanism is carried, corresponding 55 to such varying distances. In this manner there is obtained in connection with for example a sieve or screen a very effective sifting or riddling and propelling action.

In the example illustrated, the lever *e* is 60 weighted by iron or other metal plates as *i* attached to the opposite sides of the lever by studs as *j*.

The crank shaft *a* is driven through a belt as *k* or in any other convenient manner. 65

What I claim is:—

1. In free swinging mechanisms of the type aforesaid, the combination comprising a frame secured to or connected with the part or structure to be reciprocated, a crank shaft 70 journalled in said frame, and a weighted lever pivoted in the casing, said shaft having a crank pin engaged for vertical sliding movement with said weighted lever in such manner as to impart unequal rates of acceleration thereto, as set forth. 75

2. In free swinging mechanism of the type aforesaid, in combination, a frame connected to the part to be reciprocated, a crank shaft journalled in said frame, a weighted lever 80 pivotally carried in said frame, a crank pin upon said crank shaft movable in said lever away from and towards the lever pivot, and means for rotating said crank shaft whereby the weighted lever is oscillated. 85

3. In free swinging mechanism as claimed in claim 1 of the type aforesaid wherein a cover is provided for the casing, the lever being pivotally suspended from the under surface of the cover and provided at its lower portion with a vertical slot, a guide block mounted on the crank pin slidably engaged with the slot and weight members mounted on opposite sides of the lower portion of the lever. 90

In testimony whereof I have signed my name to this specification.

HUMPHREY JOHN DENHAM.
